CONTAINER SEALING MACHINE

Frank L. Darling, Teaneck, N. J., assignor, by
mesne assignments, to Crown Can Company,
Philadelphia, Pa., a corporation of Pennsyl-
vania

Application December 16, 1936, Serial No. 116,207

23 Claims. (Cl. 113—82)

The present invention relates to a container sealing machine.

The machine comprising the embodiment of the invention disclosed herein is particularly adapted to operate upon cans of the type shown in my patent for Vacuum sealing can, No. 2,024,-511, December 17, 1935, but it will be understood that the machine is applicable to other containers.

10 The principal object of the invention is to provide a sealing machine for cans and other containers and which is extremely simple in design, will operate at a high capacity, and which may be produced at very reasonable cost, and 15 also to provide a novel and efficient method of sealing containers.

Another object of the invention is to provide a machine for vacuumizing or otherwise varying pressure conditions within cans or other containers and which is of extreme simplicity, but 20 has a degree of efficiency equal to that of more involved and expensive machines.

In present vacuum canning practice the cans used are generally of two types, one type being that in which the can is finally and completely sealed by a seaming operation and must be opened with a can opener, and the other type, generally used for vacuum packed coffee, being that wherein the side wall of the can is provided 30 with a circumferentially extending rim opening seal so that the top may be removed and replaced. The second type of can is also completely or finally closed by a seaming operation.

Since both of these types of vacuum-packed cans must be finally closed by a vacuumizing and seaming machine, they are not practicable for use by the numerous small plants located throughout the country and having sales confined almost entirely to local markets. The principal reasons contributing to this impracticability is the fact that vacuumizing seaming machines are extremely expensive and the relatively small sales of a locally operating plant will not warrant the installation of such a machine. Another factor is the great size and weight of such a seaming machine, necessitating a fairly large plant constructed with a particular view of supporting the load of the machine.

The above problems are of particular importance with reference to the handling of coffee. It is now generally conceded that coffee is maintained in best condition when packed under vacuum, but at the present time, vacuum packing in cans may only be accomplished with vacuumizing seaming machines, and since these ma-

chines are too expensive for the numerous small packers throughout the country, this type of packing has not heretofore been adopted by them, and their only opportunity for competition with the larger packers has been by selling coffee packed in paper containers and by relying upon rapid sales of small shelf stocks by retailers; an arrangement of doubtful efficacy with regard to the freshness of the coffee, and altogether unsatisfactory from an operating stand-point.

The machine of the present invention operating upon a can of the type disclosed in my above mentioned patent, will produce a packed product having a more efficient seal than a can which is finally closed by seaming, but the cans may, nevertheless, be readily opened by a removable closure which is reinsertable to keep the contents in proper condition.

It is the present practice of can manufacturers to supply to packers can bodies seamed and closed at one end, it, of course, being necessary for the packer to have a seaming machine with which to finally close the other end of the can after it has been filled. By the machine of the present invention, used with the can of my above mentioned patent, can bodies having both ends seamed thereto at the can manufacturing establishment may be supplied to the packers and the latter may apply the closure of the can of my patent to one end of the can and with the machine of the present invention. By this procedure, the packer does not require a seaming machine, but he is able to market his product in a can which has a seal of an efficiency equal to that of a can which is finally closed by a seaming machine.

Since the machine of the present invention includes means to vacuumize the can, it will enable small packers to pack products such as coffee in a vacuumized can and thereby fully compete with larger packers who at the present time are the only concerns which can afford to vacuum-pack coffee or other products.

Another important object of the invention is to provide a vacuum sealing machine by means of which an efficient vacuum will be produced in such a manner that the contents of the can will not be disturbed.

In numerous vacuumizing machines, difficulty is encountered in gradually producing a vacuum in the container, the vacuum occasionally being so rapidly produced that the products are entirely withdrawn from the cans.

The flow line of the present machine includes

valves which will permit the creation of the vacuum to be regulated according to the nature of the product being handled.

Another important object of the invention is to provide a vacuumizing machine wherein the valve mechanism for controlling the vacuum is extremely simple in construction and may be readily repaired and regulated.

In most vacuumizing machines, particularly those of the rotary table type, the valve mechanism is in the form of a manifold valve of substantially one-piece construction and having a number of ports therein to simultaneously control each vacuumizing head.

The machine of the present invention includes a valve mechanism wherein each head is provided with a separate valve and the entire flow system is constructed of connections of standard construction, eliminating the necessity of an especially machined valve structure.

Another object of the invention is to provide a flow control valve of simple construction but of high efficiency, the valve being of the poppet type and having higher sealing efficiency than the usual rotary disc type valve used in multiple head vacuumizing machines.

A still further object of the invention is the provision of a sealing head which will cooperate with the can of my above-mentioned patent to form an air-tight seal between the two.

A further object of the invention is to provide a mechanism for moving containers to a position upon a rotary table and which is so designed that the possibility of containers being jammed in the mechanism is entirely eliminated.

Still another object of the invention is to provide a mechanism for moving containers from a rotary table to a stationary table, and which mechanism is entirely controlled by the rotary table through a driving arrangement of extremely simple construction.

Another object of the invention is to provide a novel form of mechanism for stopping and positioning containers beneath a mechanism for operating upon the container.

Still another object of the invention is the provision in a container sealing machine of a means to secure the caps to the containers by soldering.

Machines have heretofore been developed in which soldering operations were performed under the sealing head but such machines are extremely complicated in construction. By the machine of the present invention, acting upon a can of the type disclosed in my above mentioned patent, the containers may be closed and entirely sealed beneath the sealing heads and then moved to a soldering mechanism which operates in timed relation to the sealing heads to secure the caps to the containers. Since a greater period of time is required for the vacuumizing process than for the soldering operation, one soldering head or heating element will handle the vacuumized cans from a number of heads and the present machine is of such design that it may take advantage of this fact, thereby contributing to the low cost of the machine.

Another object of the invention is to provide a machine which will efficiently vacuumize and seal a container having a slip opening closure of the type disclosed in my patent for Vacuum sealing can, No. 2,024,511, December 17, 1935.

Other objects and advantages of the invention will be apparent from the following drawings; wherein:

Figure 1 is a front elevation of the machine;

Figure 2 is a horizontal sectional view taken on the line 2—2 of Figure 1;

Figure 3 is a front elevation of the outfeed portion of the machine, with the front cover plate removed;

Figure 4 is a central and transverse vertical sectional view taken on a line corresponding to the line 4—4 of Figure 5;

Figure 5 is a horizontal sectional view taken on the line 5—5 of Figure 4;

Figure 6 is a top view of the valve mechanism and the vacuum reservoir of the machine, with their respective cover plates removed;

Figure 7 is a vertical sectional view taken on the line 7—7 of Figure 6, the view showing one of the valves in detail;

Figure 8 is a vertical sectional view through one of the vacuumizing and sealing heads used on the machine;

Figure 9 is a top plan view of a can of the type shown in my Patent No. 2,024,511, showing the vacuumizing and sealing head in vacuumizing relation with respect thereto;

Figure 10 is a view similar to Figure 9, but showing the head in sealing and closure applying relation to the can;

Figure 11 is a top plan view of the can of Figures 9 and 10;

Figure 12 is a detail vertical sectional view through the lower portion of one side of the vacuumizing head included in the present invention; and

Figure 13 is a sectional view on the line 13—13 of Figure 8 showing the construction of the sealing sleeve used in the machine.

The machine illustrated in the attached drawings as embodying the invention may be generally described as comprising a stationary table 30 within which is mounted a rotary table 31, filled containers being delivered to the left hand end (Figures 1 and 2) of the stationary table 30 by any suitable conveyor means and positioned upon an endless infeed conveyor 32 which conducts each container to a point opposite a reciprocating transfer element or pusher 33 which positions successive containers upon platforms 34 which are vertically reciprocable in the rotary table 31. After a can, for example, has been placed upon a platform 34, and as the latter moves with the rotating table 31, the platform will rise to bring the upper end of the can in contact with the lower edge of a bell 35 forming part of the sealing and closure-applying head so that the upper portion of the can will be covered or enclosed to be sealed from atmosphere as shown in Figure 9. When vacuumizing is completed, the can will be moved further upwardly by the platform, raising the bell to the position shown in Figure 10 and to bring a closure on the can in contact with a stationary closure applying member or presser foot 36 within the bell 35 and which will firmly seat the closure on the can top. Subsequently, the can will be removed from its platform by a suitable dial or wiper 37 and moved beneath a reciprocable soldering iron or heating element 38 which will descend to solder or sweat the closure in secured position upon the top of the can, the can being stopped in proper position beneath the heating element 38 by a gate mechanism 39. At the moment that a succeeding can is moved to a position beneath the heating element, the gate mechanism 39 will be released to permit the first can to be pushed from beneath

20

50

55

the heating element and from the machine by the second can.

Supporting structure and driving mechanism

As is best shown in Figures 4 and 5, the machine is supported upon a circular base plate 45, the rotary table 31 being substantially concentric with the base plate 45, and the stationary table 30 which surrounds the rotary table and extends forwardly therefrom being supported upon pillars 46 equi-distantly spaced about the base plate as shown in Figure 5, the two front posts 46 being provided with lateral extensions 47 which support the forwardly extended portion 48 of the stationary table 30. Suitable casing plates 49 may be provided about the stationary portions of the machine to enclose the same.

The machine is driven by a motor 50 which operates a reduction gear 51 from the upper end of which extends a vertical drive shaft 52 having a pinion 53 provided at its upper end, the pinion 53 meshing with a large gear 54 fixed to a hollow main shaft 56 which extends from a point adjacent the base 45 of the machine to a point above the level of the rotary table 31, shaft 56 being journaled and supported by an anti-friction bearing 57 upon which the table 31, keyed to shaft 56 rests, the bearing 57 being in turn supported upon the upper edge of a collar 58 extending upwardly from a spider 59 provided with lateral bosses 60 which surround and are secured to the posts 46. A second anti-friction bearing 61 is provided on the shaft 56 beneath the spider 59 to hold the table against upward vertical movement. The extreme lower end of the shaft 56 moves within a socket 64 formed by an annular upward extension on the base plate 45, a tight joint being formed about the lower end of the shaft 56 by means of packing 65 positioned between the interior wall of the socket 64 and the outer surface of the shaft, the packing 65 being maintained secure by means of a gland or pressure member 66 which is kept forced downwardly upon the packing by means of bolts 67 extending therethrough and into the base 45 of the machine.

The rotary table 31 is secured to the shaft 56 by means of set screws 70 or the like. The vacuum reservoir 72 having the valved lines extending therefrom is secured to the upper end of the shaft 56, this structure being supported upon a plate 73 having a depending collar 74 thereon threaded on the upper end of the shaft, the threaded connection being secured in proper relation by a set screw 76.

The vacuum reservoir 72 is formed on the plate 73 by and within an annular wall or flange 76 extending upwardly from the plate, the upper end of the reservoir being closed by a top plate 77 tightly secured to the upper end of the flange 76 by bolts or the like. A vacuum is maintained in the reservoir 72 through a pipe 80 extending from a point below the top plate 77 and downwardly through a bushing 81 and through the shaft 56 to the base 45 of the machine, where it is connected, as by a pipe 82, to a vacuum pump, not shown. As indicated at 84, oil is maintained about the lower portion of the pipe 80 and within the hollow shaft 56, this oil serving to lubricate the bearing of the shaft within the socket 64 and also serving as a seal to prevent any air from entering about the lower end of the shaft 56 to reduce the vacuum within the reservoir 72, as might be the case if only the bushing 81 in the lower wall

of the reservoir was relied upon to maintain a seal at the lower portion of the reservoir. It will be observed that a very efficient seal is thus provided between the rotating shaft 56 and reservoir 72 and the stationary pipe 80.

As shown in Figures 4 and 5, a sprocket 85 is fixed to the shaft 56 beneath the spider 59, sprocket 85 driving a chain 86 which also engages a sprocket 87 on a vertical stub shaft 88 journaled in a plate supported from the spider 59. Shaft 88 is provided at its upper end with a bevel gear 89 meshing with a bevel gear 90 fixed to a horizontal shaft 91 journaled in depending walls of the forward extension 48 of the stationary table portion 30 of the machine. At its forward or outer end, the shaft 91 is provided with a sprocket wheel 92 which drives a sprocket chain 93 also passing about a sprocket gear 94 on a shaft 95 through which the infeed conveyor 32 is driven. As shown in Figure 2, the infeed conveyor 32 moves between guide plates 32a on the stationary table and passes beneath the surface of the table at a point beneath the transfer member 33. A second sprocket wheel 96 on shaft 91 drives a sprocket chain 97 meshing with a sprocket gear 98 on a shaft 99 and by means of which the soldering iron or heating element 38 is reciprocated, as will be hereinafter described.

As also shown in Figures 4 and 5, the rotary table 31 has a ring 105 secured to the lower ends of bosses 60 which project downwardly from the table, the ring being held to the bosses by bolts 107 extending through slots 108 in the ring and into the lower ends of the bosses. Pins 110 project downwardly from the ring 105, the pins being equi-distantly spaced about the ring and being arranged to mesh with pins 111 projecting horizontally from a collar 112 fixed to a vertical shaft 113 journaled in the upper arm 114 of a bracket 115 suitably secured in the stationary table 30, shaft 113 being operatively connected to the reciprocating transfer member 33 through the mechanism described immediately below.

The transfer member or pusher 33 is of inverted box form, with a top wall 116, outer wall 117, and an arcuate inner wall 118 which is curved on such a radius that it will fit against the side walls of cans delivered thereto by the infeed conveyor 32. The body of the pusher mounted on a frame including an inner cross member 119 having a longitudinally extending rod 120 fixed thereto and projecting rearwardly or outwardly through a sleeve 121 formed integrally with a rear cross member 122 which is fixed to a vertical driving arm 123 and is slidable with respect to the body portion of the pusher. The rod 120 is surrounded by a coil spring 124 having its rearward end bearing against the plate 122 and its forward end in contact with the cross member 119, the spring tending to hold the inner cross member 119 spaced from the outer cross member 122 as shown in Figure 4 and to hold the pusher in the position shown in that figure. If a can is not properly presented to the pusher, it will become jammed against the inner guide plate 32a when the pusher moves inwardly. In such event, the rear plate 122 fixed to the driving arm 123 may move inwardly along the rod 120 and against the action of the spring 124 without varying the position of the body and can contacting portion 118 of the pusher. Thus the can will not be crushed and no parts of the machine can be damaged. The driving arm 123 of the pusher is pivotally connected to a link 125 operatively con-

nected to a crank disc 126 secured to the stub shaft 113.

By the above arrangement, and in the normal operation of the machine, the reciprocating transfer member or pusher 33 will be in the outer position shown in Figure 2 at the moment before a platform 34 of the rotary table 31 is moved directly opposite the same. If a can is then presented against the arcuate inner face 118 of the pusher by the infeed conveyor 32, the pusher will move the can inwardly and upon the platform 34 at the moment that the platform comes directly opposite the pusher.

As is shown in Figures 2 and 4, a container engaging bracket 128 is fixed to the table 31 above and on the inner side of each platform 34 to receive and center a container on the platform.

The provision of the slots 103 in ring 105 enables the position of the ring and its pins 110 to be circumferentially adjusted with respect to the rotary table 30 so that the reciprocation of the pusher 33 will be properly timed with respect to the rotation of table 31.

Each of the vertically reciprocating container supporting platforms 34 is of circular form and includes a downwardly extending hub 130 which moves in a sleeve 131 centrally disposed with regard to a guide spider 132 cast in the rotary table 31 beneath each platform aperture of the table. The platforms 34 will of their own weight tend to move to their lowermost position, at which time their upper surfaces will be flush with the surface of the rotary table 31, each platform then resting on the upper portion of its guide spider 132. Cross pins 133 are provided in the sleeves 131 and the hubs 130 are slotted as indicated at 134 to receive these pins, this arrangement preventing the platforms from rotating. At its lower end, each hub 130 is provided with a roller 135 adapted to move on a circular cam track 136 fixed to the large spider 59 forming part of the machine frame, the cam track 136 including a low portion 137 arranged opposite the pusher 33. In clockwise succession (Figure 5), after the low portion 137, the cam track 136 also includes an incline 138, an intermediate rise 139, a second and further incline 140, and an upper rise 141 which is followed by a drop 142 to the low portion 137. The operation of the platforms 34 will be subsequently described in connection with the operation of the sealing heads or bells 35.

The sealing and closure applying heads

As best shown in Figure 6, arms 145 project from the plate 73 positioned at the upper end of the hollow shaft 56, one of the arms 145 being provided for each head of the machine, the machine in its present embodiment being equipped with five such heads. The outer end of each arm 145 is apertured to receive a tubular member 146 having its upper end threaded to receive a nut 147. Beneath the arm 145, the tubular member 146 is provided with a shoulder 148 and a collar 149 has an inwardly projecting flange positioned between the underside of the arm 145 and the upper surface of the shoulder 148, a sealing ring also preferably being positioned between the flange of collar 149 and the shoulder 148. The collar 149 is externally threaded to receive a gland nut 150 having an in-turned flange to engage beneath a flange 151 on a bendable or collapsible sealing sleeve 152, preferably formed of rubber.

The sealing sleeve 152 is also provided with a

flange 151 at its lower end which is secured beneath the inwardly projecting flange of a gland nut 153 threaded to the upper end 154 of the bell member 35. A coil spring 155 is positioned about the tubular member 146 within the sealing sleeve 152 and the upper portion 154 of the bell, the upper end of spring 155 bearing on the lower surface of the shoulder 148 and the lower end of the spring extending into a counterbore 156 in the upper extension 154 of the bell and bearing upon the lower end of the counter-bore. By this arrangement, the bell is tended downwardly to the position shown in Figure 8, the sealing sleeve 152 forming a seal between the tubular member 146 and the bell. The sealing sleeve 152 is bowed outwardly intermediate its length, as shown in Figure 8, being maintained in this position by a metal ring 157 cast in the sleeve at the apex of its bowed portion.

The bell 35 is of generally cup-shaped form with its lower portion open, and in its normal downward position the upper wall 159 of the bell bears upon a gasket 160 seated in a ring 161 threaded on the lower end of the tubular member 146. Immediately above the upper surface 21 of the gasket 160, the tubular member 146 is provided with apertures or ports 163, which ports will normally be closed from the bell because of the fact that the lower surface of the upper wall of the bell bears on the gasket 160. The lower 30 end of the tubular member 146 is closed by a stud 165 having its upper end threaded into the lower end of the tubular member below the ports 163. The stud 165 is threaded at its lower extremity to receive the closure applying head or presser foot 36 which is so mounted on the stud that it will be positioned somewhat above the lower edge of the bell 35.

By the above arrangement, the interior of the bell will normally be closed from communication with the interior of the tubular member 146, but may move upwardly along the tubular member to open the ports 163. The closure applying head 36 is rigid on the tubular member and has no vertical movement.

The lower edge of bell 35 is provided with a stepped and circumferential groove, the deepest portion of the groove, indicated at 168, being adapted to receive a rubber sealing ring 169 which is adapted to bear upon the upper surface 50 of a can or other container to be vacuumized. The shoulder or step 170 of the groove is adjacent the exterior surface of the sealing ring 169 so that a shallow and open groove 171 is provided adjacent the sealing ring to receive the upwardly extending circumferential flange with which the tops of tin cans are normally provided. The outer wall 172 of the groove 168 is tapered downwardly and outwardly from the shoulder 170, so that when the upwardly projecting flange of a can moves upwardly toward the shoulder 170, it will be centered with respect to the shoulder.

A means is provided to force cans downwardly from the bell, this means comprising a plurality of bent spring elements 173, one of which is shown in detail in Figure 12. As shown in the latter figures, each spring is secured to the outer wall of the bell and its inner end generally conforms to the wall 172 and the shoulder 170, but is normally spaced from these surfaces by its own resiliency. However, when a can bears against the spring, as shown in Figures 9 and 10, the inner portion of the spring will seat in a

radial groove 174, so that it will lie flush with the surfaces 172 and 170.

As is shown in Figures 6 and 8, the upper end of each tubular member 146 communicates with the vacuum reservoir 72 through a line generally designated by the numeral 175, each line preferably formed of suitable pipe fittings including a valve 176 which operates to place the tubular element 146 in direct communication with the reservoir, and a valve 177 which is operated to place the tubular member 146 in communication with the atmosphere.

Each line 175 also includes a manually operable valve 178 which may be set to properly regulate the vacuum action and so that its effect upon a container will not be too sudden.

The vacuum controlled valve 176 and the atmospheric valve 177 are of identical construction and, for this reason, only the atmosphere controlled valve 177 is illustrated in detail, this valve being shown in Figure 7.

Referring to Figure 7, the valve there shown comprises a tubular body 180 threaded at both ends, with a wrench receiving portion provided between the threaded portions. Within the valve body 180, there is positioned a sleeve-like valve element 182 provided with a bore 183. The inner end of the bore 183 is closed as indicated at 184 and includes a radially extending annular flange 185 having a rubber gasket 186 seated in its inner face and arranged to contact with the end of the valve body 180 within the fitting 187. The valve member 182 is provided with inlet bores 187 spaced slightly inwardly from the contact surface of the gasket 186 and has other bores 188 provided in its far end, the latter end being closed by a plug 189 which also comprises a contact member to engage a cam by means of which the valve is operated. Valve member 182 is normally held in the position shown in Figure 7 by means of a coil spring 190 having one end bearing on the valve body 180 and its opposite end bearing on the closure or contact member 189. In the closed position of the valve, no flow may occur through the sleeve-like valve member 182 because the ports 187 are within the valve body member and the gasket 186 is in contact with the end of the body member. Obviously, if the valve element 182 is forced to the right 50 from the position shown in Figure 7, flow may occur through the ports 187, bore 183 and ports 188, or in the reverse direction.

When the valve of Figure 7 is used as an atmospheric valve 177, it is mounted as shown in Figure 7 in a fitting 191 included in each line 175 closely adjacent the upper end of the tubular member 146, the threaded portion distant from the contact member 189 being threaded into the fitting 191. The contact member 189 will thus project from the casing covering the upper portion of the machine to be operated by a striker member in a manner hereinafter set forth. When the contact member 189 engages the striker member, the valve element 182 will be moved to the right from the position shown in Figure 7 so that atmospheric pressure may flow inwardly through the ports 188 and through the bore 183 to the bent open ports 187.

When the valve of Figure 7 is to be used as a vacuum flow controlling valve, the threaded portion of the body member 180 is engaged in an aperture in the wall 76 of vacuum reservoir 72 so that the contact member 189 will be within the reservoir and subject to operation by a cam member within the reservoir. When the cam

moves the contact member 189 toward the body member 180, air will be drawn from the pipe line 175 through the ports 187, valve bore 183 and ports 188 into the reservoir 72.

It will be observed that the valve illustrated in Figure 7 is extremely efficient in providing a close seal under operating conditions involving a vacuum, the spring 190 serving to hold the packing ring 186 in close engagement against the adjacent end of the valve body 180, the compression of the sealing ring 186 in an axial direction simultaneously causing the packing ring to have a close fit within the groove in flange 185. Furthermore, in the event of wear of the sealing ring 186, a new ring may readily be substituted merely by driving out the tapered pin 189a which holds the contact member 189 in the valve member 182 so that the spring 190 may be released and the valve element 182 entirely removed from the valve body.

Since a vacuum control valve 176 and an atmosphere valve 177 are included in each of the lines 175 leading to the tubular member 146 associated with each bell 35, a vacuum may be provided within each bell after it has been raised from the gasket 160 as hereinafter described, or atmospheric pressure may be directed to the interior of the bell.

The vacuum valves 176 are controlled by a cam 197 shown in Figures 4, 6 and 8 as secured to the upper end of the vacuum pipe 80 within the vacuum chamber 72. As best shown in Figure 6, the cam 197 includes a low surface 198 provided on the portion on which the contact member 189 of a vacuum valve 176 will bear when the bell 35 and can supporting platform corresponding to that valve are directly opposite the reciprocating transfer element or pusher 33. In a clockwise direction, from the low portion 198, the cam 197 is then provided with an incline 199 leading to a high portion 200 of some length and which terminates at a relatively sharp decline 201 leading back to the low portion 198.

Operation of vacuumizing and closure applying heads

In the operation of vacuumizing and closing containers set forth below, such operation is set forth as it would occur with a can of the type disclosed in my patent for Vacuum sealing can, No. 2,024,511, issued December 17, 1935. As shown in Figures 9 and 10, such a can 210 includes a top wall 211 having an upwardly extending peripheral flange 212 formed by the seaming of the top 211 to the body of the can. Spaced slightly inwardly from the flange 212 is an annular groove 213, and spaced somewhat further inwardly from this groove is an aperture 214 of the can defined by an upwardly and outwardly inclined lip 215 which terminates in an upwardly facing and relatively sharp edge indicated at 216. The lip 215 projects upwardly from an annular groove or trough 217, this groove being defined on its outer side by an upwardly and outwardly inclined wall 218.

The closure or cap 220 used on the can is of the slip type and includes a central recessed portion 221 having side walls 222. A laterally extending flange 223 is provided on the closure at the upper end of the side wall 222, the laterally extending flange being provided with an upwardly facing annular groove 224. As illustrated in Figures 9 and 10, the annular pocket on the under surface of the closure 220 defined by the side wall 222

and the under and inner surface of the groove 224 is filled with suitable plastic sealing compound indicated at 225 and into which the lip 215 of the can top is intended to project as hereinafter described when the can is in completely sealed condition. Points 226 project laterally from the outer edge of the closure 220 beyond the groove 224, three of these points normally being circumferentially spaced about the closure. As described in my above mentioned patent, the points 226 have solder and flux applied thereto before the closure is placed upon the can.

The cans 210 are delivered to the machine by any suitable mechanism, preferably immediately after the cans have been filled, and with the closures 220 merely resting in the apertures 214 of the cans, so that while the skirt 222 of the closure will be substantially centered within the lip 215 of the can top, the upper edge 216 of the lip will not project into the body of the sealing material 225.

The continuously moving infeed conveyor 32 will bring successive cans opposite the reciprocating transfer member 33 and at the moment that a container supporting platform 34 of the rotary table comes opposite the transfer member, the latter will move the can inwardly upon the platform, the can being substantially centered upon the platform by the arcuate bracket 128. At this moment, the platform 34 which receives the incoming can has its upper surface flush with the surface of the rotary table 31, the roller 135 (Figure 4) which controls that platform being on the low portion 137 of the cam track 136. Also, the atmospheric valve 177 associated with the bell 35 above the platform 34 will be closed due to the action of its springs 190. The vacuum control valve 176 associated with the bell will also be closed, due to the fact that its contactor 189 will at this moment be opposite the low portion 198 of the valve operating can 197 as shown at A in Figure 6.

As the rotary table 31 moves in a clockwise direction (Figure 6), the platform roller 135 will move upwardly on the incline 138 of cam track 136, so that the top wall of the can will contact with the lower surface of bell 35 in the manner shown in Figure 9, the upwardly extending edge flange 212 of the can contacting with the incline 172 of groove 170 on the lower edge of the bell to center the can about the sealing ring 169 of the bell and so that the sealing ring will bear on the top of the can immediately outside of the annular groove 218 in the top of the can. The platform and can will move upwardly sufficiently far to raise the bell 35 on the tubular member 40 and against the action of the coil spring 165 until the ports 168 in the tubular member are opened or exposed to the interior of the bell. At this time, the cam roller 135 of the platform will have reached the intermediate high portion 139 of the can track 136 so that the can will rise no further for a substantial portion of the rotation of the rotary table 31. Immediately after the can has been raised to the position described above, the contactor 189 of the vacuum control valve 176 associated with that bell will have come opposite the rise 199 on the valve control can shown in Figure 6 at position B, causing the vacuum valve to open so that the vacuum effective in vacuum reservoir 72 may act through the corresponding line 176, tubular element 146 and through the ports 168 to create a vacuum in the bell 35. Since the closure 220 is only lightly pressed in

the aperture 214 of the can, a vacuum will thus be exerted in the interior of the can.

As shown in Figure 9, when the top wall of the can is in firm contact with the bell, the shoulder 169a adjacent the inner side of the sealing ring 169, and which projects downwardly past the lower end of the ring, will fit into the groove 213 in the can top wall. The vacuum condition in the bell will then tend to draw the sealing ring inwardly against shoulder 169a and down into the groove 213 so that a tight seal is provided. The provision of the shoulder 169a is desirable because it contacts with the can top to prevent the latter from deforming the sealing ring, as would occur if the movement of the can against the sealing ring were not limited as is done by the shoulder.

It will also be noted that the upper wall 171 of groove 170 will not contact with the top of can flange 212. Such contact would of course interfere with the seal between the can and bell.

In the preferred operation of the machine, the manual valve 178 in the vacuum line 175 is only opened to such an extent that a sudden high vacuum will not be created, the machine relying upon a continued gradual drawing of vacuum to the desired stage, rather than a sudden action to attain such stage. In line with that purpose, the vacuum control valve 176 will be held open for approximately 180 degrees of rotation of the rotary table, and until the contactor 189 of the vacuum control valve comes opposite the decline 201 of the valve control cam 197. However, just prior to the moment when the vacuum control valve closes, the roller 135 of the container platform 34 will move up the incline 140 to the high portion 141 of can track 136, this action causing the can to force the bell 35 further upwardly on the tubular element 146. The additional raising of the can 210 will bring the closure 220 in contact with the stationary presser foot 36, as shown in Figure 9, the flange 36a of the presser foot bearing on the flange 223, of the can closure 220. As a result, the closure will be forced tightly downwardly into the aperture 214 of the can, causing the relatively sharp upper edge 216 of the lip 215 of the can to be embedded in the plastic 225 in the closure. However, as described in my above mentioned patent, the shoulder formed by the under surface of the annular groove 224 in the closure will contact with the surface 217 of the can top before the lip 215 can cut entirely through the plastic 225. Also, at this time, the points 226 on the closure will contact with the top 211 of the can. The can will thus be sealed with its contents maintained in a vacuum.

Immediately after the closure has been applied to the can to seal the same in the manner described above, the vacuum control valve 176 will be closed as described above, thereby closing off communication between the vacuum reservoir 72 and the bell 35. However, a vacuum condition will still exist within the bell and in the line 176 outwardly of the vacuum control valve 176, but this vacuum will be eliminated by the opening of the atmosphere valve 177 resulting from contact of its contactor 189 with the atmosphere valve trip 280 (Figures 1 and 2) mounted on a post 281 extending upwardly from the stationary table 30. Atmospheric pressure will then flow into the bell 35 and line 176 and just subsequently to this the roller 135 of the container supporting platform 34 will move down the incline 142 of cam track 136 to the low portion 137 of

137 of the track, thereby carrying the container 210 downwardly, the bell 35 likewise moving downwardly by the action of the spring 155 until its upper wall seats upon the gasket 160 to seal the ports 163. Because of the close contact between the top of the can and the sealing gasket 163, a can may at times tend to adhere to the bell but this adhesion will be broken by the light spring 173 so that the can will move downwardly 10 from the bell with the platform and to a position flush with the surface of the rotary table 31.

It will be observed from the above that the final control of vacuum flow is obtained by the upward movement of each bell 35 upon its tubular element 146, caused by contact of a can 210 therewith. Hence, if no can is presented beneath a bell, no waste of vacuum effect will occur.

The outfeed dial and heating element

20 In the embodiment of my invention shown in the present drawings, the containers will be moved from the platforms 34 and rotary 31 by an outfeed dial 37 rotatably mounted on a stud 235 projecting upwardly from the stationary table 30. With a five platform rotary table, a dial provided with three arms 236 is found satisfactory. The dial 37 is caused to rotate by the action of upwardly projecting lugs 237 spaced about the periphery of the rotary table 31, these lugs 30 being so spaced and positioned and the dial 37 being so positioned and having its arms so spaced and curved that after one movement given the dial by a lug 237, the arm of the dial which will then be at the position marked 236c will project 35 very slightly inwardly over the surface of the rotary table 31. The next lug 237 coming toward the dial with the rotation of the rotary table will move behind or to the right of the arm at 236a, with the result that the dial will be turned in a 40 counterclockwise direction as the lug brushes behind the arm to finally move it to the position indicated at 236b.

The rotation of the dial 37 described above will, with the cooperation of a fixed guide member 238 45 which projects over the rotary table 31 from the stationary table 30, move the can to the position shown at C in Figure 2 and the next movement of the dial will position the can at C directly beneath the soldering iron or heating element 38. The dial will be stopped in proper position by engagement of a spring-pressed element 239 in 50 one of three notches spaced about a disc 239a fixed to the upper end of stud 235. The casing for the spring-pressed element 239 is fixed to one 55 of the arms of dial 37.

The can is stopped beneath heating element 38 by a gate mechanism 39 including an arm 240 which projects from an inner guide member 241. The guide member 241 and an outer guide member 242 cooperate to insure that the container will move in a straight line after it has left the heating element 38. The gate mechanism 39 is controlled by the arms 236 of outfeed dial 37 in a manner hereinafter set forth.

65 As shown in Figure 3, the heating element 38 includes an electrically heating unit 245 receiving current through a lead 246, the unit being carried at the outer end of an arm 247 which extends inwardly and laterally from a vertical 70 rod 248 having a plunger 249 at its lower end which is reciprocable in a housing 250 mounted on the upper side of the outer guide member 242. A coil spring 251 is provided in the housing 250 above the plunger 249 to tend the plunger to 75 downward position, the plunger 249 also being

provided with a roller 252 which contacts with the cam 98 fixed to the horizontal shaft 99. The cam 98 has a number of spaced high portions 253 designed to lift the heating element 245 after each can has been sweated or soldered and to then permit the heating element to be moved downwardly by the action of the spring 251 and into close contact with the points 226 of the closure or cap 220 of a can.

Because of the fact that the points 226 of the 10 can closure have already been provided with solder before being delivered to the present machine, only a very brief contact of the heating element 245 with the can will be necessary to cause the solder to be melted or sweated so that 15 it will flow upon the top 211 of the can so that when the solder hardens it will hold the closure in the desired position on the can as described in my above-mentioned Patent No. 2,024,511, the heating element thus serving as a closure securing 20 means.

After the closure securing means 38 has acted upon the can, the gate mechanism 39 will be released or moved inwardly in the direction indicated by the arrow in Figure 2, and by reason of the fact that the succeeding partial rotation of the outfeed dial 37 will cause the arm of the spider indicated at the position 236c to brush against a horizontally extending plate 258 secured to an arm 259 horizontally slidable in a 30 fixed bracket 260. The inner end of the arm 259 is pivotally connected to the inner end of the gate arm 240 so that when the plate 258 is moved to the right, the gate arm 240 will be swung in the direction of the arrow to lie flush with the 35 inner guide member 241. The can simultaneously being moved from position C by the outfeed dial 37 will then contact with the can beneath the now raised heating element 38 to move the latter can to the right. Immediately thereafter, the arm of 40 dial 37 which has been in contact with the gate control plate 258 will move out of contact with this plate and the latter will then be returned to the position shown in Figure 2 by the action of a coil spring 263 which surrounds the arm 259 between the bracket 260 and the plate 258, with the result that the gate arm will be restored to the position shown in Figure 2 so that the can moving toward the heating element 38 will be stopped in proper position beneath the latter. 45

It will be obvious that the movement of successive cans away from the heating means 38 will cause cans to be successively pushed from the right hand or outfeed side of the machine.

It is to be noted that the counterbore 156 in 55 the upper portion 154 of the bell 35 extends into the upper portion of the bell such an extent that only a relatively small area 154a of the bell is in contact with the tubular element 146. The clearance between portion 154a and the tubular member 146 is such that the bell may rock or tilt 60 relatively to the tubular element 146 in the event that a can presented beneath the valve is slightly tilted. It will be noted too that the bowed resilient sealing sleeve 152 will permit such tilting of the 65 bell on the tubular element 146 without affecting the sealing of all of the elements from atmosphere. Obviously, the use of any well known type of gasket or packing gland for providing a seal at the point sealed by the sealing sleeve 152 would prevent any tilting movement of the bell. Furthermore, if the usual type of packing were 70 employed at this point, it would require continuous adjustment, for if the packing were maintained too tightly in engagement at the point of 75

sealing, the bell would not slide freely, while if the packing were too loose, leakage would result.

The provision in the sealing sleeve 152 of a means such as the ring 157 to maintain it against collapse is also important. For example, were it not for the ring 157, or some similar arrangement, the sleeve 152 would tend to crease or bend inwardly upon itself on a longitudinal line at the bowed portion. The inner upper and lower faces 10 of the sleeve are also provided with relatively crossed ribs 152a as shown in Figure 13, these ribs preventing the inner upper and lower walls of the sleeve from closely contacting with each other when moved together by the folding of the 15 sleeve as the bell moves upwardly and when a vacuum condition exists in the sleeve.

It will be understood that the invention is not limited to the details of construction shown in the drawings, and that the example of the use of the 20 machine and mechanisms which has been given does not include all of the uses of which they are capable; and that the phraseology employed in the specification is for the purpose of description and not of limitation.

25 I claim:

1. The combination in a vacuum sealing machine of a container platform, a source of vacuum, a bell supporting element having a passage therein adapted to communicate with said source of 30 vacuum, a bell arranged to move with respect to said bell supporting element and normally out of communication with the vacuum passage, means to move said platform with respect to said bell to present a container to the latter, and thereby 35 move said bell with respect to said supporting element to place the bell in communication with the vacuum passage.

2. The combination in a vacuum sealing machine, of a source of vacuum, a bell supporting 40 element having a passage therein adapted to communicate with said source, a bell arranged to move with respect to said element and normally positioned out of communication with the passage, and means to move a container into contact with 45 said bell to move the latter with respect to said supporting element and place the bell in communication with the vacuum passage.

3. The combination in a vacuum sealing machine, of a container platform, a source of 50 vacuum, a bell supporting element having a passage therein adapted to communicate with said source of vacuum, a bell movable with respect to said supporting element, means to move said platform with respect to said supporting element to 55 cause a container thereon to engage said bell, and cooperating valve elements respectively carried by said supporting element passage and bell and arranged to be operated upon movement of said bell with respect to said supporting element 60 to place the passage in communication with said bell.

4. The combination in a vacuum sealing machine, of a container platform, a bell supporting element having a passage therein, a source of 65 vacuum adapted to communicate with said supporting element passage, a bell movable with respect to said bell supporting element, a presser foot within said bell and fixed with respect to said supporting element, means to move said platform with respect to said supporting element to cause a container thereon to engage and move 70 said bell, cooperating valve means carried by said supporting element passage and said bell, respectively, to place said bell in communication with 75 said passage when a container initially moves the

bell with respect to said supporting element, and means to additionally move said platform to cause the container thereon to move said bell further with respect to said supporting element and cause the container to contact with said 5 presser foot.

5. The combination in a vacuum sealing machine, of a rotary table, means to deliver partially closed containers to said table, a vacuumizing bell associated with said table, a vertically rigid presser foot within said bell to close and seal containers, a vertically reciprocable platform to position containers in contact with said bell and subsequently move the container closure into contact with said presser foot, vertically reciprocable closure securing means spaced from said table, and means to move containers from said table to said last-named means. 10 15

6. The combination in a vacuum sealing machine, of a container platform, a bell supporting 20 element of tubular form, a source of vacuum in communication with said supporting element, a bell movable with respect to said bell supporting element, a presser foot within said bell and fixed at the lower end of said tubular supporting element, means to move said platform with respect to said supporting element to cause a container thereon to engage and move said bell, cooperating valve means carried by said supporting element and said bell, respectively, and operated by 25 movement of said bell with respect to said supporting element to place said bell in communication with said source of vacuum when a container initially moves the bell with respect to said supporting element, and means to additionally move 30 said platform to cause the container thereon to move said bell further with respect to said supporting element and cause the container to contact with said presser foot. 35

7. A vacuumizing structure for containers comprising a tubular element, a container engaging bell slidable on said element, cooperating valve means carried by said element and said bell, respectively, and adapted to place said bell in communication with said element when said bell is 45 moved with respect to said element, and a resilient sleeve secured to said element and said bell to provide a seal between the same. 40

8. A vacuumizing structure for containers comprising a bell, the lower edge of said bell being 50 provided with a resilient ring adapted to contact with the top of a container body, and means on said bell to free a container therefrom after the container has been vacuumized.

9. The combination in a vacuum sealing machine, of a vacuum reservoir, a flow valve comprising a body element of sleeve form, a tubular valve element having a radially extending flange at one end thereof and ports in its wall spaced longitudinally from said flange, means to urge 60 said flange into contact with one end of said body element and hold said ports within said element; and valve operating means within said reservoir. 55

10. A vacuumizing structure for operation upon a container provided with a peripheral flange projecting upwardly from its top wall, comprising a bell member having a sealing ring in its lower edge adapted to bear upon the top wall of the container, and a groove adjacent said ring adapted to fit over the peripheral flange on the container, the outer wall of the groove being downwardly and outwardly inclined to cooperate with the peripheral flange of the container to center the container with respect to the bell member. 65 70 75

11. A vacuumizing structure for operation upon 75

5 a container including a top wall having a closure-receiving opening therein and a groove surrounding the opening, comprising a bell member having a downwardly projecting sealing ring in its lower edge adapted to bear upon the top wall of the container adjacent the outer edge of the groove, and an annular shoulder on the lower edge of the bell immediately adjacent the sealing ring and adapted to fit in the container top wall 10 groove to limit downward movement of the bell with respect to the container.

12. The combination in a container handling machine, including a rotating table, of means to move containers from the rotary table comprising 15 a dial rotatably mounted adjacent the table and having arms extending over a portion of the table surface, and trip means spaced about the periphery of the table and adapted to contact with said arms adjacent the axis of the dial to rotate the latter to remove containers from the table, adjacent arms of the dial having their side walls curved to substantially coincide with the path of movement of the trip means so that the initial and final portions of each movement of the dial 25 will be accelerated.

13. The combination in a container handling machine including means to perform an operation upon a stationary container, of means to move a container beneath said means, an element to stop containers beneath said operation performing means, and means controlled by said container moving means to hold said element in container stopping position.

14. The combination in a container handling machine including means to perform an operation upon a stationary container, of a rotating dial to move a container beneath the operation performing means, means to stop containers beneath the operation performing means, and means to hold said last-named means in container stopping position and constructed and arranged to be released from container stopping position by contact of a dial arm therewith during rotation of said dial.

15. The combination in a container handling machine including means to perform an operation upon a stationary container, of a rotating dial to move a container beneath the operation performing means, means to stop containers beneath the operation performing means, means to urge said last-named means to container stopping position, said last-named means being positioned in the path of movement of said dial and adapted to be released upon contact of a 55 dial arm therewith.

16. A vacuumizing structure for containers comprising a bell arranged to contact with the top of a container body, and means on the lower portion of said bell to free a container therefrom after the container has been vacuumized. 5

17. The combination in a vacuum sealing machine, of a rotatable vacuum reservoir, a flow valve carried by said reservoir, and a stationary cam within said reservoir to actuate said valve.

18. The combination in a machine for creating 10 a predetermined pressure condition within a container, of a fluid flow line to establish such pressure, a sealing head reciprocable thereon, and means to seal said head to said line comprising a longitudinally bowed collar, and means within 15 said collar to maintain the same in bowed condition.

19. The combination in a container sealing machine, of a support, a bell slidable on said support, and adapted to contact with a container, 20 said bell being in contact with said support over a limited area to enable it to tilt with respect thereto.

20. The combination in a container sealing machine, of a support, a bell slidable on said support, and adapted to contact with a container, 25 said bell being in contact with said support over a limited area to enable it to tilt with respect thereto, and means to provide a seal between the support and bell throughout the range of sliding 30 and tilting movement of the bell.

21. The combination in a container sealing machine, of a support, a bell slidable on said support, and adapted to contact with a container, 35 said bell being in contact with said support over a limited area to enable it to tilt with respect thereto, and means within said bell to prevent its inner surfaces from closely contacting with each other when the same is bent.

23. A sealing collar bendable and outwardly bowed intermediate its ends to provide opposed 40 inner shoulders, one of said shoulders being provided with a series of projections to prevent the same from having abutting and circumferentially uninterrupted contact with the other of said shoulders. 45

23. A sealing collar bendable and outwardly bowed intermediate its ends to provide opposed inner shoulders, each of said shoulders being provided with a series of ridges thereon to prevent the same from having abutting and circumferentially uninterrupted contact from each other, the ridges of the respective shoulders extending at an angle to each other. 50
